UNITED STATES PATENT OFFICE

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

DESIGN FOR A GUARD FOR AN OPHTHALMIC MOUNTING

Application filed August 26, 1929. Serial No. 32,535. Term of patent 14 years.

To all whom it may concern:

Be it known that I, NELSON M. BAKER, a citizen of the United States, residing at Southbridge, in the county of Worcester and State of Massachusetts, have invented a new, original, and ornamental Design for a Guard for an Ophthalmic Mounting, of which the following is a specification, reference being made to the accompanying drawings, forming a part thereof.

Fig. I is a front view of a guard for an ophthalmic mounting showing my new design.

Fig. II is a side view of same.

Fig. III is a section taken on line III—III of Fig. I.

Fig. IV is a perspective view showing in dotted lines the guard arm and its attachment to the lens rims to disclose the appearance of the guard when in use.

I claim:

The ornamental design for a guard for an ophthalmic mounting as shown and described.

In testimony whereof, I affix my signature.

NELSON M. BAKER.
